R. E. HALL.

CHAFING ROLLER FOR WAGONS.

(Application filed Mar. 27, 1900.)

(No Model.)

FIG. 1.

FIG. 2.

FIG. 3.

UNITED STATES PATENT OFFICE.

ROBERT E. HALL, OF MANKATO, KANSAS.

CHAFING-ROLLER FOR WAGONS.

SPECIFICATION forming part of Letters Patent No. 657,821, dated September 11, 1900.

Application filed March 27, 1900. Serial No. 10,383. (No model.)

To all whom it may concern:

Be it known that I, ROBERT E. HALL, a citizen of the United States, residing at Mankato, in the county of Jewell and State of Kansas, 5 have invented certain new and useful Improvements in Chafing-Rollers for Wagons; and I do hereby declare the following to be a full, clear, and exact description of the invention, such as will enable others skilled in the 10 art to which it appertains to make and use the same.

This invention has relation to means for preventing injurious contact of the wheels with the body of a timber-wagon or other vehicle, particular attention being devoted to the disposition of the parts so as to prevent binding of the wheel and pitching or upward movement of the wagon-body by the riding of the wheel thereunder when turning the 20 wagon in a limited space.

The means consist of a roller constituting a fender or rub iron and mountings therefor of special construction and disposition with reference to the wagon-body and adjunctive 25 parts thereof, and which will appear more fully in the subjoined description.

For a full description of the invention and the merits thereof and also to acquire a knowledge of the details of construction of the 30 means for effecting the result reference is to be had to the following description and the drawings hereto attached.

While the essential and characteristic features of the invention are necessarily susceptible of modification, still the preferred embodiment thereof is illustrated in the accompanying drawings, in which—

Figure 1 is a perspective view of a fragmentary portion of a wagon-body, showing 40 the application of the invention, the parts being inverted and a portion broken away. Fig. 2 is a perspective view of the parts seen in Fig. 1 similarly related, but viewed from the opposite end. Fig. 3 is a perspective view 45 showing the invention applied and the manner of its operation.

Corresponding and like parts are referred to in the following description and indicated in all the views of the drawings by the same 50 reference characters.

The wagon or vehicle body may be of any construction and is strengthened by the bol-

ster 1, stake 2, and brace 3, the stake consisting of a metal rod having its upper portion flattened and bent to embrace the upper 55 edge portion of the side 4 of the wagon-bed, the lower end of the brace being threaded and passing through an opening in the outer end of the bolster 1 and receiving a nut 5. The brace 3 is bolted or otherwise secured at 60 its upper end to the stake and side 4, and its lower end is threaded and passes through an opening in the outer end of the bolster 1 and receives nuts 6, between which the outer portion of the bolster is clamped. A rub-iron 7 65 is secured to the angle formed between the side 4 and the bottom 8 of the wagon-bed and is disposed to have the wheel come in contact therewith when making a short turn.

A hanger or bracket is secured to the bottom side of the bolster 1 and comprises a plate 9, flange 10, and rib or brace 11. The plate 9 is pendent from the body or bed of the wagon and occupies a vertical position and is approximately of triangular outline, the 75 apex being at the lower end. The flange 10 is an integral part of the plate 9, is located at a right angle thereto, and is bolted to the bolster 1, the lower ends of the stake 2 and braces 3 passing therethrough and serving as 80 fastening means for connecting the outer end portion of the hanger to the projecting portion of the bolster 1. The rib or brace 11 occupies about a central position with reference to the length of the flange 10 and extends therefrom to and along the outer side 85 of the plate 9. The parts 9, 10, and 11, comprising the hanger or bracket, are preferably formed of a single casting, which obviates the formation of joints and enables the part 90 to be cheaply manufactured.

The companion hanger or bracket comprises a plate 12, of approximately triangular form, the brace 13 at the outer edge of the plate 12, and flanges 14 and 15, disposed at a 95 right angle to each other and at the top edges of the respective parts 12 and 13 and adapted to receive the bolts, by means of which the hanger or bracket is secured to the bottom of the wagon body or bed. The upper edge portion of the brace 13 projects a short distance above the plane of the flange 15 to form a lip 16, which overlaps the vertical side of the wagon-bed and prevents inward displacement 100.

of the hanger or bracket in the event of the bolts becoming loosened. It is to be remembered that the stress or force is applied from the outer side, and the lip 16, bearing against the vertical side of the wagon-bed, relieves the fastenings of the greater part of the strain which would otherwise come thereon. Hence a limited number of fastenings may be employed for securing the hanger to the wagon-body without fear of the part becoming loosened or detached. A strap of iron 17 is bolted to the side 4, and its upper end is bent to embrace the top edge portion of said side, and its lower end is bolted to the brace 13.

15 The plates 9 and 12 project to an equal distance from the plane of the bottom 8 and are apertured in longitudinal alinement to receive a bolt 18, upon which a roller 19 is mounted for rotation and which constitutes the rotary fender or rub-iron. This roller 19 is set in from a vertical plane touching the outer face of the side 4 a distance to enable the wheel to come in contact therewith and at the same time touch the fixed rub-iron 7, thereby preventing jamming of the wheel or a riding of the wagon-bed thereon, both of which features are objectionable. The outer edge of the plate 12 inclines inwardly toward its lower end to provide ample clearance for the wheel.

15 The mountings for the rotary fender 19 are such as to enable the invention to be applied to any vehicle-body and upon both sides thereof and are stiffened and braced in such a manner as to sustain the strain and load imposed thereon when turning the wagon in a comparatively-small space.

15 The bolt 18, forming the spindle for the roller 19, is headed and shouldered at one end in the usual manner and is provided at its opposite end with a nut to hold it in place. This spindle or bolt is loose, so as to turn in the hangers and distribute the wear upon all sides.

45 Having thus described the invention, what is claimed as new is —

1. The herein-described means for preventing injurious contact of a vehicle-wheel with the body when making short turns, the same comprising an upper fixed rub-iron, companion brackets or hangers pendent from the bed, one of the brackets having a vertical lip extension to overlap the side of the wagon-bed,

and a roller supported by the lower ends of the brackets and located inside of a vertical plane touching the outer face of the side of the bed to which the means are applied so that the wheel will touch the roller and the aforementioned rub-iron at the same time, substantially as set forth. 60

2. The herein-described means for preventing injurious contact of a vehicle-wheel with the body when making a short turn, the same comprising a hanger consisting of a plate, a flange at the upper edge of the plate, and a centrally-disposed rib between the flange and plate, said hanger being disposed to project a short distance from the adjacent side of the bed to which it is attached, a second hanger comprising a vertical plate, a brace at the outer edge of said plate and having a lip extension at its top edge to overlap the side of the bed, and flanges at the upper ends of the plate and brace, and a roller supported by the lower ends of the hangers, the last-mentioned hanger being disposed with the brace about in the plane of the side of the bed, substantially as set forth. 70

3. In combination with a wagon-body provided with a bolster, a hanger secured to the bottom side of the bolster and comprising a vertical plate, a horizontal flange and a centrally-disposed brace, a stake and brace therefor secured to the side of the wagon-bed and having their lower ends serving to connect the outer end portion of the flange of the hanger to the projecting portion of the bolster, a companion hanger secured to the bed and comprising a vertical plate, a brace at the outer edge of the plate and about in the plane of the side of the wagon-bed and having its upper edge portion overlapping said side, and flanges at the upper ends of said plate and brace, an iron secured to the side of the wagon-body and having its lower end portion made fast to the brace of the last-mentioned hanger, and a roller supported between the lower ends of the companion hangers, substantially as set forth. 80

In testimony whereof I affix my signature in presence of two witnesses.

ROBERT E. HALL.
